UNITED STATES PATENT OFFICE.

JOHN H. McMURRAY, OF SCHENECTADY, NEW YORK, ASSIGNOR OF ONE-HALF TO JOHN T. GORMAN, OF COHOES, NEW YORK.

GAS-COCK.

1,139,208.

Specification of Letters Patent. Patented May 11, 1915.

Application filed August 20, 1914. Serial No. 857,794.

To all whom it may concern:

Be it known that I, JOHN H. McMURRAY, a citizen of the United States, residing at Schenectady, in the county of Schenectady and State of New York, have invented new and useful Improvements in Gas-Cocks, of which the following is a specification.

This invention relates to improvements in gas cocks and more particularly to a safety gas cock of that type wherein the cock is locked in its closed position in such manner that it cannot be accidentally moved therefrom.

The principal object of the invention is to provide a gas cock of the type stated which shall be simple and practical in its structural nature, readily operated to open position, and automatically locked in closed position.

With the above and other objects in view, the invention consists in the novel features of structure, relation and combination which will be particularly pointed out as the description proceeds.

An embodiment of the invention is illustrated in the accompanying drawings wherein:—

Figure 1 is a front elevation of the gas cock in which the features of the invention are incorporated. Fig. 2 is a top plan view thereof. Fig. 3 is a side elevation thereof, partly in longitudinal section. Fig. 4 is a longitudinal sectional view thereof showing the locking element in position to release the plug. Fig. 5 is a horizontal section on the line 5—5 of Fig. 4, and Fig. 6 is a detail perspective view of the locking key.

Similar characters of reference designate corresponding parts throughout the several views.

The gas cock shown is of the usual turning plug type and includes the casing 1 having an inlet connection 2 and an outlet connection 3. The casing 1 has the usual tapered bore intersecting the connections 2 and 3 and provided to receive a turning plug 4 of the usual form. The turning plug 4 has at its upper end and beyond the casing 1, a head 5 which carries an operating handle 6.

The casing 1 is provided near its upper end on its inner face with an annular channel 7 which is overhung by a flange 8, the latter fitting snugly against the plug 4. The flange 8 is provided at a suitable point with

a notch or recess 9 communicating with the channel 7 and extending to the upper face of the casing 1. The plug 4 is locked in closed position by a key 10 which is provided with a laterally projecting finger 11 and below the finger 11 with a centering extension 12. The key 10 is fitted in a recess 13 which extends to the circumferential face of the head 5 and its extension 12 is fitted in a bore 14 arranged centrally and axially of the plug 4 and below the recess 13. The recess 13 corresponds in width to the width of the key 10 and communicates with an enlarged recess or socket 15 extending to the upper face of the head 5 and arranged centrally and axially thereof. The key 10 carries at its upper end an operating knob or button 16 which has a somewhat snug fit in the recess 15 but is of less depth than said recess. The key 10 is urged upwardly by a suitable spring, preferably an expansion coil spring 17 which is arranged in the recess or socket 15, under the button 16 and which bears against the base of said recess or socket and the under face of said button. In the closed position of the plug 4, the key 10 is elevated by the spring 17 and its finger 11 engages in the notch 9, as shown in Fig. 3. By virtue of the engagement of the finger 11 in the key 10 of the notch 9, the plug 4 is positively locked in its closed position. To move the plug 4 to open position, it is first necessary to depress the key 10. For this purpose, the button 16 is pressed downwardly by the thumb and the finger 11 is moved from the notch 9 into the channel 7. Thereupon, the plug 4 may be turned in the usual manner. The movement of the plug beyond its full open position is prevented by a stop pin 18 which projects into the channel 7 and which is engaged by the finger 11 when the key comes into its full open position. When it is desired to close the plug, it is turned in the usual manner and when it reaches its closed position, the finger 11 alines with the notch 9, at which time, the spring 17 acting on the knob or button 16 raises the key and causes the finger 11 to enter the notch 9 as above explained. The movement of the plug beyond its closed position is prevented by a stop pin 19 located under and at one side of the notch 9 and which is engaged by the finger 11 when the key comes to its closed position.

The upward movement of the key 10 under the pressure of the spring 17 is prevented by a stop pin 20 fitted in the head 5 and having its end engaging loosely in a shallow recess 21 formed in the adjacent side of the head.

Having fully described my invention, I claim:

In a gas cock, a casing, a turning plug 10 fitted therein and having a projecting head provided with a lateral recess extending to its circumferential face, the head having at its upper end an axially located recess with which said lateral recess communicates and 15 having an axially located bore projecting downwardly from said lateral recess, the casing having its inner face provided near its upper end with a circumferential channel and having a flange overhanging said 20 channel and provided with a notch extend-

ing between said channel and the upper face of the casing, a key mounted in said lateral recess for sliding movement in the direction of the axis of the casing and having a laterally projecting finger formed to engage 25 in said notch, the key also having below said finger a centering extension which engages in said bore, an operating button secured to the upper end of the key and arranged in said axially located recess and an expansive 30 spring also arranged in said axially located recess under said operating button and engaging the same.

In testimony whereof I have hereunto set my hand in presence of two subscribing witnesses.

JOHN H. McMURRAY.
